[54] CYAN DYE-FORMING COUPLERS

[76] Inventor: Philip T. S. Lau, c/o Kodak Park Works, Rochester, N.Y. 14650

[21] Appl. No.: 280,594

[22] Filed: Jul. 6, 1981

[52] U.S. Cl. 568/716; 430/17; 430/384; 430/385; 430/552; 430/553

[57] ABSTRACT

Novel phenolic cyan dye-forming couplers contain in the 2-position a p-cyanophenylureido group. These couplers are useful in photographic emulsions, elements and processes.
